LABORATORY FUME HOOD

Ronald E. Hill, Independence, Mo., assignor to Hill Engineering & Manufacturing, Inc., Independence, Mo., a corporation of Missouri

Filed Mar. 18, 1964, Ser. No. 79,068

Term of patent 7 years

(Cl. D16—2)

Fig. 1.

Fig. 2.

FIG. 1 is a perspective view of the laboratory fume hood.

FIG. 2 is a top plan view thereof.

The undisclosed side panel of the fume hood is substantially the same as the side shown, the rear is flat and unornamented.

I claim:

The ornamental design for a laboratory fume hood, as shown and described.
